UNITED STATES PATENT OFFICE.

EGBERT VON LEPEL, OF BERLIN-CHARLOTTENBURG, GERMANY.

CURRENT CONVERTER FOR IGNITION SYSTEMS.

Application filed March 25, 1925, Serial No. 18,253; and in Germany August 18, 1924.

All electric igniting devices hitherto known in connection with internal combustion engines did not result in full satisfaction as interruptions in the working of the 5 sparking plug occurred in spite of the provision of condensers and spark-gaps. Also the connection of the sparking plug in series with a quenching spark gap and a capacity in parallel with the source of electric power 10 has not succeeded in securing a proper ignition of the sparking plug under all circumstances.

Now, I have discovered that the reason of the failure is due to the action of weak 15 maintained currents, which are components of the ignition current, upon deposits of soot or condensed particles present on the insulator or between the electrodes of the plug, converting the respective deposit into 20 carbon, and incrusting this into the surface of the insulator. While the loose particles of soot and the said condensed particles disappear, as a rule, spontaneously at full load 25 of the engine, the incrusted particles adhere firmly and form constant conducting bridges for a certain part of the current, in consequence whereof these bridges increase gradually so that the operation of the spark plug gets finally completely prevented. On this 30 discovery my present invention is based.

My invention is illustrated diagrammatically and by way of example in the accompanying drawings in which Figure 1 reveals the principle on which the invention is 35 based; Figure 2 is another diagram also dealt with in the specification; Figures 3 and 4 show a section and an elevation of a high-frequency current-converter for carrying 40 my invention into effect in a particularly economical way; and Figure 5 is also a wiring diagram into which this converter is inserted.

As is known, the failure of ignition in explosion motors is due very frequently to the 45 fact that deposits of soot, oil, or dampness, which set up a shunt to the spark gap, are formed on the surface of the spark plug insulation or between the poles of the spark gap in the spark plug. If the ohmic resistance of such shunt circuits is great in comparison to the resistance which the spark gap of the spark plug presents, then only very little current will flow through the shunt. But if the resistance of the shunt 55 gradually becomes less, then the percentage, of the whole available current, which passes

through the shunt gradually increases. With a certain value of ohmic resistance of the shunt circuit, there will then pass through the shunt circuit a percentage of the whole 60 available current which is so great that the difference in potential which is necessary for the formation of the spark cannot be available.

It was first determined that the portion of the current which flows through the shunt has the effect of reducing the ohmic resistance of the shunt. This effect is to be explained by the intense heating resulting from the current, of the thin layer which forms 70 the shunt. The ohmic resistance of a thin conducting layer which is present in the circuit in shunt with the spark gap of the spark plug is decreased very much in the course of time by the ignition current itself, so that 75 the portion of the current which flows through the shunt increases constantly.

It was furthermore determined as a basis for the present invention that the duration of each ignition current impulse in the case 80 of the ignition devices in use up to now is comparatively long. The reason therefore is the following: In the case of the usual high tension ignition devices—whether they are formed as ignition coils with battery ignition or as magnets—the current is produced by the electromagnetic field of an iron core. The secondary winding on the iron core has a very high self-induction, in order 85 that the high tension may be produced which is necessary to break through the original resistance of the spark gap of the plug. As soon as the spark is formed the original high resistance of the spark gap falls immediately to a comparatively small value. A 90 luminous arc is thereby formed which with respect to the secondary winding of the coil functions similarly to a short circuit. The magnetic field in the iron is maintained for 95 a very long time by the practically short-circuited coil, so that it can give up its energy only very slowly and in the form of a long continued weak current. Consequently the time during which the ignition current flows is much longer than is expedient for ignition. 100

According to my discovery it is useful in case of the plugs being defiled by soot or the like, to have the necessary electric tension of the plugs rising as steeply as possible 105 and to have it act as short as possible upon the sooted plug.

The simplest way of performing this

could consist in storing the whole electric energy of each ignition-period in a sufficiently large condenser, and to discharge the stored-up energy in one short and strong spark through the spark-plug by means of inserting one of the well-known types of quenching-gaps like those used in wireless transmission.

This way, however, proves to be unsuitable for the reason, that the necessarily varying number of revolutions of the motor is not allowing the use of a sufficiently large condenser as the electric energy is far from being constant but using a smaller condenser even with a quenching gap of the best type known it is impossible to prevent the low-frequency component existing after the high-frequency discharge from passing through the spark-plug, as the time required by the usual type of quenching-gaps for their de-ionization is much too long for the purpose.

I therefore aimed at an arrangement allowing to fully interrupt the current at a rate of some hundred thousand times in a second, so obviating the necessity of having a storing condenser of appreciable capacity.

The new means to fully interrupt the ignition-current at a rate of several hundred thousand times per second are the following:

Instead of a quenching spark-gap a storing-up gap is used, which consists of a series of electrodes the spark-gaps between the latter being not wider than from some thousandths to a few hundredths of a millimeter, whereas the spark-gaps of the usual quenching-gaps amount to at least between one and two tenths of a millimeter.

Using a series of gaps of the very short type indicated, the self-capacity of the source of high-tension combined with the self-capacity of the circuit wires, which amount together to from 20 to 40 cm., is sufficient to act as storing-up capacity; the shape of the potential-curve resulting from inserting such series of very short gaps into the leads to the spark-plug is diagrammatically shown in Fig. 1.

In this figure the dotted line 1 represents the tension produced by the high-tension source its terminals being open. The curves 2 represent the tension as it acts upon the spark-plug. From this diagram it is to be seen, that the potential necessary to break down the gap of the plug rises very steeply on the plug to the value 3, a damped high-frequency oscillation of a frequency of about some millions per second taking place at the first discharge and dying out before the second discharge of the same ignition-period begins, and so strong and short high-frequency impulses will occur a great number of times during each ignition period, combusting the deposits on the plug instead of incrusting them. Besides thereof, by the

electrostatic action of these impulses the electrodes and the insulator of the spark-plug get constantly and very effectively cleaned, because the loose deposits of soot or moisture are thrown off with considerable power. 70

In the intervals between these impulses the plug is fully kept free of tension, this latter rising up slowly on the storing gap, charging meantime the said small self-capacity.

The new process is therefore based thereon, that the current of long duration which normally flows through the spark plug is suppressed, in that an arrangement is combined with the high tension circuit, which interrupts the current flow each time immediately after it originates and again restores it immediately after the interruption. Through this alternate breaking of and restoring the current flow, the current is split up into a series of short impulses rapidly following each other. Any current interrupter acting sufficiently quickly can, in principle, be used for this purpose. 75 80 85

The apparatus for converting the primarily low-frequency current into high-frequency current-impulses and consisting merely of a series of about 4 to 8 small electrodes with the said very small gaps, will in the following be called the high-frequency current-converter. 90 95

For the sake of completeness the diagram figure represents the curve of tension 2^a at the plug, when no gap is used in series with the plug. As is to be seen from this diagram, the potential at the plug is slowly increased to the breakdown-voltage 3^a of the plug-gap. Thereafter a short oscillatory flush of current takes place diminishing the resistance of the gap so much that a continuous electric arc is maintained until the ignition-period is finished. 100 105

During all this time the plug remains under tension and more or less strong components of the current are flowing through the soot, carbonizing and incrusting it into the insulator. 110

On comparing Figs. 1 and 2 it is apparent that the whole time of the discharge process is shortened. The shortening, in fact, is very much greater than appears in the drawings, for with breaks and makes of the current circuit ensuing with sufficient rapidity, the whole time of discharge can be reduced to less than a tenth part of the normal time. The new process presents itself therefore as a very important concentrating of energy, and effects, accordingly, a likewise important increase in the strength of the ignition current. This effect is even more important than the prevention of the short circuiting of the spark plugs. For it makes the application of the new ignition process advantageous even for such motors as are not unfavorably affected by oil or soot on the plugs. 115 120 125

In order to manufacture a reliable high-

frequency current-converter it is very important to choose the most suited material for the electrodes. The usual materials, viz., copper, brass or nickel, are very bad for this purpose.

Except some expensive precious metals, as for instance wolfram, those other metals are especially suited, the fusing or combustion point of which is below or very near their 10 temperatures of incandescence. Metals of this kind are, for instance, aluminium, tin, magnesium and high-grade alloys thereof. The use of these metals, etc., for series spark-gaps has been hitherto entirely unknown in 15 the art of motor ignition.

It is advisable to select metals, the residues of combustion of which or the oxides of which are nonconductive, as is the case especially with aluminium, magnesium, and 20 their alloys.

When using electrodes of these materials no great parallel sparking surfaces are required as is the case with the known quenching-gaps. The electrodes may be ball-shaped or even pointed. No cooling-provisions are further needed.

It is sufficient to arrange the right number of electrodes with a loose microphone-like contact to one another and to have by 30 the discharge itself the surfaces burned or oxidized. Thereafter the residues of combustion or the oxides themselves serve to keep the electrodes in the right very short distance apart from one another.

35 It has been proved very practical to devise the high-frequency current-converter in the shape of a small cable-socket as shown in Figs. 3 and 4, or to insert it into the body of the plug itself as it requires very little space.

In Figure 3 a section through a socket-shaped converter is shown. 10 represents a small insulating tube which contains the electrodes 11, 12, 13; these electrodes forming, for instance, seven gaps of the said very short length. The end-electrode 11 is provided in the example shown with a hole and a screw 14 for fixing it on the high-tension pole of the plug, and the other end-electrode 50 13 has a smaller hole 15 to take up the lead wire. The details of the converter may, of course, be modified.

It is furthermore practical to separate from one another the fresh electrodes to start with by means of a thin layer of paper or lacquer, these substances burning slowly away in the course of using the apparatus and being no longer needed, when the said self-insulating layer of oxide has formed.

60 Fig. 5 shows how the converters may be inserted in the leads. The converters 16 are placed each in series with one spark-plug 17.

Of course, as well a single converter might be placed between the source of voltage 65 18 and the distributor 19.

The number of electrodes to be used depends on the voltage and on the output of energy of the source of tension.

Using, for instance, seven gaps the whole drop of tension between the ends of the converter for getting the described effect need not and should not exceed the amount of potential drop produced by a single ordinary gap of about from 0,5 to 1,5 mm.

The great difference between the present 75 converter and the well-known quenching gaps consists in the following features:

The lowest voltage by which a spark could be produced under normal conditions amounts to about 300 volts even if the gap 80 should be the smallest imaginable. Increasing the width of the gap the drop of the potential on the gap increases in this way, that to the initial voltage-drop is added the drop caused by the air-space. While 85 the initial drop is practically constant, the drop on the air-gap is extremely variable under the action of the current passing through that gap; the initial drop shall in the following be called the cathode fall. 90

In my converter having those very short gaps I chiefly make use of the constant cathode fall obviating as much as possible the influence of the air space for obtaining the storing-up function. That is why my 95 converter re-establishes so instantaneously its storing-up effect, whereas the well-known quenching-gaps have a comparatively large air-space between their electrodes so that the de-ionizing of these spaces requires 100 a much longer time, in consequence whereof, in order to prevent an arc from being maintained a condenser of great capacity must be provided for keeping the voltage off for that time. My high-frequency current-converter therefore increases effectively the output of the source of current, whereas with all other known gaps the current on the plug gets considerably weakened.

It is an advantage of the new current converter that it regulates the whole ignition energy and thereby uses up only as little potential as a standard spark gap of about 0.2 to 0.4 millimeters length at usual air pressure.

I finally state that, besides the two ways I have now described, i. e., either shunting the plug by a high-frequency choker or converting the energy into a series of high-frequency impulses following one another 110 very rapidly, other means may give similar effects in execution of my principal claim, i. e., the necessity of obviating the damaging effect of the usual weak ignition-current impulses, which are maintained throughout 120 each ignition-period.

I claim:

1. A current interrupter for the high tension circuit of an ignition circuit for internal combustion engines comprising an auto- 130

- matically and periodically varying resistance in the ignition circuit between the high tension coil and the spark plug; said resistance varying automatically within wide limits, so that the resistance of the high-tension circuit is varied several times between the limits of approximately zero and infinity during each magnetic impulse of the ignition apparatus.
10. 2. A current interrupter for the high tension circuit of an ignition circuit for internal combustion engines comprising a plurality of gaps interposed in the ignition circuit between a high tension coil and a spark plug to create large resistance variations of the ignition circuit, the increase of resistance with decreasing current occurring in said gaps taking place so rapidly that a series of current interruptions take place at each magnetic impulse of the ignition apparatus.
15. 3. A current interrupter for the high tension circuit of an ignition circuit for internal combustion engines comprising a plurality of electrodes forming a plurality of gaps interposed in the ignition circuit between a high tension coil and a spark plug to create large resistance variations of the ignition circuit, the increase of resistance with decreasing current taking place so rapidly that a series of current interruptions take place at each magnetic impulse of the ignition apparatus, said electrodes consisting of a material which when oxidized by the passage of the spark current form an oxide which is a non-conductor of electricity.
20. 4. A current interrupter for the high tension circuit of an ignition circuit for internal combustion engines comprising a plurality of electrodes forming a plurality of gaps interposed in the ignition circuit between a high tension coil and a spark plug to create large resistance variations of the ignition circuit, the increase of resistance with decreasing current taking place so rapidly that a series of current interruptions take place at each magnetic impulse of the ignition apparatus, the electrodes consisting of a material which when oxidized by the passage of the spark current form an oxide which is a non-conductor of electricity and
- the distance of the electrodes forming the gap are maintained by the oxide therebetween.
5. A current interrupter for the high tension circuit of an ignition circuit for an internal combustion engine comprising a casing of insulating material open to the atmosphere; and a plurality of electrodes in the casing forming a plurality of gaps for creating large resistance variations in the circuit causing a series of current interruptions at each magnetic impulse of the ignition apparatus.
6. A current interrupter for the high tension circuit of an ignition circuit for an internal combustion engine comprising a casing of insulating material having a vent therein forming communication with the atmosphere; and a plurality of electrodes in the casing forming a plurality of gaps for creating large resistance variations in the circuit causing a series of current interruptions at each magnetic impulse of the ignition apparatus.
7. A current interrupter for the high tension circuit of an ignition circuit for internal combustion engines comprising a tube of insulating material open to the atmosphere; a plurality of aluminium electrodes in said tube to form narrow gaps in order to create a series of strong current impulses of momentary intensity at the spark plug; and means in the tube and cooperating with the end electrodes for securing a contact with a lead-in wire at one end of the interrupter and for securing contact with the spark plug at the other end.
8. A current interrupter for the high tension circuit of an ignition circuit of an internal combustion engine comprising a casing of insulating material open to the atmosphere; and a plurality of aluminium electrodes in the casing forming a plurality of gaps for creating large resistance variations in the circuit causing a series of current interruptions at each magnetic impulse of the ignition apparatus.

In testimony whereof I affix my signature.

EGBERT VON LEPEL.
